MEANS FOR DELIVERING CUT GRAIN FROM
A HARVESTER TO A BINDER

Walter W. Russell, Waterloo, Iowa

Application August 7, 1935, Serial No. 35,141

3 Claims. (Cl. 56—446)

My invention relates to improvements in communicating mechanisms between a harvester and a binder, and an object of my improvements is to provide a simplified, relatively inexpensive and convenient means for carrying cut grain from the one to the other.

Another object of my improvements is to include in this carrying mechanism devices for engaging and propelling by a step by step action cut grain in parcels from the harvester to a binder.

Another object of my improvements is to associate with such step by step propelling means auxiliary devices at the beginning and end of the same for initiating the above functions to the point of action of a binding mechanism upon the successive parcels of cut grain delivered to it.

I have accomplished the above objects by the mechanism which is hereinafter described and claimed, and which is illustrated in the accompanying drawing.

Fig. 1 is a rear elevation of my said mechanism as associated operatively with parts of a harvester and a binder, only certain coacting elements of which are shown in use with my said mechanism. Fig. 2 is a detail top plan of a binder needle in association with the mechanism which is employed by a step by step movement in passing on cut grain into the scope of action of a binder.

The mechanism of many such delivery mechanisms is often very complicated and of costly construction, and my apparatus for this purpose may be easily associated with the cutting and delivery mechanism of a harvester, to receive the cut grain therefrom and supply it in parcels to the binding and knotting mechanism of harvesters.

The figures of the drawing are diagrammatic in character for convenience, and it is obvious that various changes may be effected in the different features and elements of my apparatus without departing from my invention or the scope of protection thereof as stated in the accompanying claims.

The numeral 1 denotes the extended platform of a harvester as seen from the rear, and on this is mounted a rotary shaft 3 carrying an endless belt 4 and rotated by any convenient connection to the harvester mechanism not shown. On a sprocket wheel not shown on the farther end of the shaft 3 is carried a sprocket chain 5. Forward of the shaft 3 posts or other supporting means 10 carry in bearings a crank-shaft 11 having a pair of oppositely directed cranks 12 and 13 thereon intermediate the posts. On one end of

the crank-shaft 11 is a sprocket wheel 43 carrying the forward part of the chain 5. Between the shafts 3 and 11 a horizontal shaft 7 is supported in bearings in spaced posts and carries a plurality of separated star-wheel teeth 8, while on the front end of the shaft 7 is mounted a sprocket wheel 6 between and engaged by the sprocket chain 5 as shown in said Fig. 1. The numeral 9 denotes a fixed and inclined runway deck extending upwardly and forwardly relative to the adjacent end of the traveling apron 2 to receive cut grain from the latter.

On any suitable fixed support or brackets 44 depending from the farther end of the deck 9 on a pivot shaft 31 is mounted a binder needle 15 35 of a well known type, by means of a medial arm 33—34. The apertured point of the needle is above and a little forwardly of said shaft 11, when in its lowered position beneath said deck.

Above this needle and the deck 9 on a fixed 20 standard 27 or other supporting means is mounted a rotary shaft 22 carrying a packer wheel 21 from which projects a packer arm 23 radially. On the shaft 22 is also mounted a cam 24 having an edge notch with which a traveler wheel 25 25 on a movable rod 26, being elements of a binder mechanism, is in contact along the rim of the cam and at times locked releasably in its notch. Other features of the binder and knotter means are not shown, not being included in my invention. 30

On the forward face of the packer wheel 20 are bevel gear teeth 21 engaged by a bevel pinion 19 on an upright shaft 18, the lower end of the shaft carrying a bevel pinion 17 in mesh with a bevel pinion 16 fixed on the crank-shaft 11, but not shown in Fig. 2.

On the crank-pins of the cranks 38 and 39 are pivotally mounted the grain propeller arms 36 and 37 of the same shape and dimensions and having forwardly concaved finger parts 47. These arms are spaced apart circumferentially on the shaft 11, and to traverse, as do certain elements 8 and 35, a longitudinal slot in the deck 9. 40

On pivots as at 40 on the brackets 44 are pivoted the forward ends of swingable rods 38 and 39 respectively, and whose rear ends are pivoted as at 46 to the shanks of said arms 36 and 37. An arm 32 projects from the pivot 31 and is pivotally connected to an upright member 29 which carries a link having a pivotal connection at 30 with the packer wheel 20. By this means the needle member 33 is rocked to and fro, to cooperate with a binder and knotter not shown, in the binding and securing of twine about parcels of cut grain which 50 55

are propelled in succession up the deck by means of the fingers 47 of the arms 36 and 37 in turn. The numeral 28 denotes a forward supporting arm mounted to reciprocate at times to close the forward end of the deck 9 to serve as a stop for a parcel of cut grain propelled forwardly by one of said arms 36 or 37, and to hold the parcel while being twined and knotted, but the mechanism for actuating the arm 28 is not shown, being old in this art.

Operation.—Cut grain is delivered from the traveling apron 2, where it is picked up by the star-wheels 8 which move it forwardly into the paths of action of the step by step arms 36 and 37 as they are oscillated in turn on the crank-pins 45 by rotation of the shaft 11, as limited by the scope of movements of the swinging arms 38 and 39.

In synchronism the shaft 18 and packer wheel 20 are rotated by the shaft 11. A quantity of grain propelled forwardly by one of the arms 36 or 37 into the sphere of action of the needle 33, is shaped into a parcel by the rotating arm 23 on the packer wheel 20, the latter driven by the crank-shaft 11 through the medium of the shaft 18 and its end gearings 16 and 17, and 19 respectively, where the parcel is tied into a sheaf by the rising and rocking needle 33, as held by the rockable arm 28, on the deck 9, and cooperating binding and knotting devices not here illustrated.

When the sheaf thus formed and tied after recession of the respective pusher arm 36 or 37, and separation of the tying twine at the knotter, the arm 28 recedes to clear the sheaf which is discharged from the deck by the rotating arm 23. The arms 36 and 37 in turn rise, penetrate grain on the deck 9, carry it forward past the needle 33 which is in its downward position, and which then rises to string the parcel in a sheaf in the usual way. The arms 36 and 37 sink successively through the deck opening so that the arms move through the deck substantially upwardly and downwardly and so as to least obstruct the passing grain during said operations. The invention herein therefore relates to the means used for transferring the cut grain from the traveling apron 2 to deliver it within the scope of action of the needle 33 and other devices for binding, knotting and severing the binding twine before the bound sheaf is expelled by the arm 23 as the other arm 28 subsides below the level of the deck.

It is therefore important in my invention to supply mechanism of an intermediate character to satisfactorily perform the above functions,

while by the simplest and cheapest means, for economy, lightness of the assemblage and ease of action in practice.

I claim:

1. A carrying mechanism positioned to receive cut grain and transport it in parcels to a binder, comprising the combination with an apertured upwardly inclined deck, of a rotatable shaft beneath the deck, having cranks thereon, arms rockably mounted on the cranks and having terminals protrusible successively in turn upwardly through the apertured deck and then recede wholly below the deck in alternation to penetrate passing grain to separate it into parcels for binding into sheaves by propelling the parcels in alignment into the field of operation of binding mechanism, and linking means pivotally connected to supports and to said terminals to limit their play and cause them to rise through the inclined deck and then recede entirely below the deck. 20

2. A carrying mechanism positioned to receive cut grain and transport it in parcels to a binder, comprising the combination with an apertured deck of arms movably connected to each other and to the deck to be protrusible therethrough and return below the deck in turn successively to penetrate passing grain and divide it into parcels propelled into the field of operation of a binder, and a rotatable shaft having thereon a plurality of transversely spaced star-shaped wheels adapted to receive the cut grain from a harvester and pass it into the field of operation of said arms. 30

3. A carrying mechanism positioned to receive cut grain and transport it in parcels to a binder, comprising the combination with an upwardly inclined deck having bearing apertures, of a rotatable shaft below the deck having thereon arms protrusible through the deck to receive cut grain from a harvester and deliver the grain upon the inclined deck, movably connected and limited arms below the deck having terminations successively protrusible successively upwardly and then wholly downwardly in turn through the apertured deck to penetrate passing grain from said shaft arms while separating it into successive parcels for binding into sheaves, releasable oscillatory abutment means for retaining the parcel while being bound, and other movable means for compressing the parcel into a sheaf while being bound and knotted and then discharging the bound sheaf when released by said abutment means. 45 50
